(57) **CLAIM**

The ornamental design for a pet toy, as shown and described.

DESCRIPTION

FIG. 1 is a front, top perspective view of a pet toy, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, bottom perspective view of the pet toy, shown in an environment of use;

FIG. 10 is a rear, top perspective view thereof;

FIG. 11 is another front, bottom perspective view of the pet toy, shown in an environment of use; and,

FIG. 12 is a rear, top perspective view thereof.

The evenly spaced broken lines are shown for the purpose of illustrating both parts of the pet toy as well as environmental subject matters. None of the broken lines form part of the claimed design.

1 Claim, 12 Drawing Sheets
